DETACHABLE HAMMER HEAD FOR
ROTARY BEATERS

Alexander J. Roubal, Milwaukee, Wis., assignor
to Allis-Chalmers Manufacturing Company,
Milwaukee, Wis.

Application June 14, 1951, Serial No. 231,601

12 Claims. (Cl. 241—197)

1

This invention relates to hammer mills and more specifically to a renewable hammer element for the same.

Hammer mills having a rotor with a number of hammer arms pivotally mounted on the rotor with each pair of such arms having renewable hammer elements detachably secured thereto are well known. In such mills it is advantageous to have hammer elements of the type which are reversible so that a new breaking edge, on the same hammer element, may be presented when one breaking edge has become worn.

It is an object of the present invention to provide a new and improved detachable hammer element of the type which is reversible end for end about an axis radial to the rotor shaft, and which may be additionally reversible about an axis parallel to the rotor shaft, and which may be detached from the hammer arms, to allow such reversals, without dismantling the hammer arms from the rotor.

The invention having the above and still further objects and advantages will appear more fully from this specification and the accompanying drawing in which:

Fig. 1 is a vertical sectional view through a hammer mill casing showing a series of hammer arms with removable hammers mounted thereon;

Fig. 2 is an end view of a hammer assembly including a portion of a hammer arm and locking means for fastening the hammer to the hammer arms;

Fig. 3 is a partial longitudinal sectional view taken on line III—III of Fig. 2;

Fig. 4 is the same end view shown in Fig. 2 except that the hammer arm and locking means are omitted;

Fig. 5 is a cross sectional view taken on line V—V of Fig. 3;

Fig. 6 is a cross sectional view taken on line VI—VI of Fig. 3 except that the hammer arm is omitted;

Fig. 7 is a perspective view to an enlarged scale of elements comprising the locking means shown in Figs. 2 and 3;

Fig. 8 is a partial longitudinal sectional view of a hammer assembly embodying a modified form of hammer and locking means therefor;

Fig. 9 is an end view of the hammer assembly shown in Fig. 8;

Fig. 10 is a cross sectional view taken on line X—X of Fig. 8;

Fig. 11 is a partial longitudinal section of the hammer shown in Fig. 8 but is shown equipped with a modified form of locking means; and

2

Fig. 12 is a cross sectional view taken on line XII—XII of Fig. 11.

Referring more particularly to the drawing, Fig. 1 shows a rotary hammer mill which consists essentially of a series of rotatable elements which are located within a housing or casing 5. A main shaft 6 is rotatably mounted in bearings (not shown) supported by side walls of casing 5 and has a suspension member or disk 7 fixed thereto. Disk 7 is provided with spaced openings in which pins 8 are mounted and secured as by cotter pins. Pins 8 are arranged parallel to each other and pivotally mounted on each pin is a pair of hammer arms 9 which may be respectively mounted and locked against end displacement by any suitable means. The radially outer ends of each pair of axially spaced arms 9 have mounted thereon a hammer 10. It is the specific structure of hammers 10 to which the present invention relates but such structure is only diagrammatically shown in Fig. 1.

Hammer mills of the type referred to herein are usually provided with removable casing portions so that the interior of the mill may be inspected, repairs made and worn hammers replaced. A demountable attached casing portion 11, which forms no part of the present invention, is shown in Fig. 1, by way of example, in the upper right hand quadrant of casing 5.

Hammer arms 9 may assume various shapes but each arm is herein illustrated as having a neck portion of narrow width and a head portion 17 of somewhat wider width than the neck portion, forming abutments adjacent the neck portion. Both the head and neck portions are shown as having axially extended portions relative to the hammer arm proper, in a direction parallel to pins 8, but this is merely a matter of design.

Referring to Figs. 2 to 7, hammer 10a is illustrated as a one piece rectangular unit of cast or welded construction with an inverted, generally U-shaped cross section and comprising a pair of oppositely facing, spaced, generally rectangular breaker bar portions 24 and 25 and a bridge portion 26 connecting and extending longitudinally between the upper parts of the bar portions. The bar portions 24 and 25 may be considered as having opposed spaced rear surfaces 24' and 25' and spaced impact surfaces 24'' and 25''. Projecting respectively from the lower edges of rear surfaces 24' and 25' are a pair of longitudinally extending ribs 27 which structurally strengthen the hammer.

Provided respectively at the ends of hammer

10a are longitudinal channel portions 28 and 29, for respectively receiving the heads of a pair of hammer arms 9, which are formed between the rear surfaces 24' and 25' of the bar portions 24 and 25. Channel portion 29 has an opening through the end surface 30 of the hammer for receiving therethrough the head and neck portions of a hammer arm 9.

Provided intermediate the ends of hammer 10a is an assembly slot 32 which is formed between the rear surfaces 24' and 25' of the bar portions 24 and 25 for receiving the head and neck portions of a hammer arm 9 from a radial direction opposite bridge portion 26. Channel portion 28 has an opening, communicating longitudinally with assembly slot 32, through which the head and neck portions of a hammer arm 9 in the assembly slot may be received.

Channel portions 28 and 29 are each provided with a pair of horizontally opposite, parallel, longitudinally extending ridges, 33 and 34, and the ridges of each pair project respectively from the rear surfaces 24' and 25' of the bar portions 24 and 25. The crests of the respective ridges 33 and 34 in each channel portion 28 and 29 are spaced apart a distance less than the width of the head portion of a hammer arm 9 but greater than the width of the neck portion.

One end of hammer 10a is provided with abutment means 35, which may be a transversely extending wall positioned longitudinally adjacent channel portion 28. Spaced from the other end of hammer 10a by a distance which may be somewhat greater than the axial length of the head portion of a hammer arm 9, for use with which it is designed, is a similar wall or abutment means 36 positioned between assembly slot 32 and channel portion 29.

In effect it is seen that the spacing between rear surfaces 24' and 25' is slightly greater than the width of the head portion of a hammer arm 9 and the length of ridges 33 are so chosen that there is sufficient open space between the ends of such ridges and abutment means 36 to form assembly slot 32 for receiving the head portion 17 of a hammer arm during assembly. Ridges 33 and bridge portion 26 create the effect of a narrower slot, channel portion 28, adjoining assembly slot 32, to accommodate the head portion of a hammer arm 9 with the neck portion of the arm extending between ridges 33. Ridges 34 and bridge portion 26 similarly create the effect of a slot, channel portion 29, which accommodates the head portion of a hammer arm 9.

When the head portions of a pair of hammer arms 9 are disposed respectively in channel portions 28 and 29, hammer 10a is prevented from being radially displaced by the engagement of ridges 33 and 34 with the hammer arm head portions. Various locking arrangements to limit longitudinal displacement of hammer 10a relative to the head portions of a pair of hammer arms 9 so as to maintain the hammer in an operative position may be devised, and one such arrangement is illustrated herein by way of example. It will be understood that some longitudinal "play" between the hammer and arms may be permitted.

Locking elements for engagement with hammer 10a are shown in detail in Fig. 7. One of the elements is a rectangular retainer plate 38 having a centrally mounted threaded stud 39 projecting therefrom. Formed for cooperation with plate 38 is a generally T-shaped plate 40 having lugs 41 projecting perpendicularly from the ends of the horizontal portion of plate 40. Plate 40

has formed therein a centrally located aperture 42 for receiving stud 39.

The right hand end of channel portion 29 is provided with a transverse, generally rectangular retainer slot 43 which is formed between bar portions 24 and 25 and normal to bridge portion 26 in longitudinal proximity to the end of the hammer. In effect, slot 43 is formed by merely eliminating portions of ridges 34 and ribs 27 so as to provide a space of sufficient depth, width and thickness to accommodate retainer plate 38. The end portions 34a and 27a of ridges 34 and ribs 27, adjacent and to the right of slot 43, form a cruciform 44, in cross section, which accommodates T-shaped plate 40 such that the lugs 41 of plate 40 are respectively positioned between ridge portions 34a and rib portions 27a.

With the hammer arms 9 in the position shown in Fig. 3, retainer plate 38 is inserted into transverse slot 43 so as to prevent relative longitudinal movement between the hammer and arms. T-shaped plate 40 is inserted into cruciform 44 with threaded stud 39 projecting through aperture 42 of plate 40. Plates 38 and 40 are then fastened together by means of a nut 45 which engages threaded stud 39 and, as lugs 41 of plate 40 engage rib portions 27a in abutting relation, plate 38 is thereby demountably secured in slot 43.

Hammer 10a is of the type in which the impact surfaces 24" and 25" can be selectively reversed so as to permit use of both of the upper longitudinal edges before requiring replacement of the hammer. As the outer leading edges of each hammer wears rapidly, frequent reversals and replacements of the hammers are necessary.

A primary feature of the invention is that hammer 10a may be reversed to present a new leading edge or replaced with another hammer without necessitating the dismounting of hammer arms 9 from disk 7. Disassembly of hammer 10a from arms 9 is readily accomplished by first removing the locking assembly (which may be the locking arrangement described above by way of example), sliding hammer 10a to the left until the head of the left hand hammer arm 9 is in assembly slot 32 and then lifting hammer 10a radially away from arms 9. Hammer 10a may then be reversed end for end, so as to present a new leading edge, and again mounted on hammer arms 9, or be replaced with a new hammer, without disconnecting the hammer arms 9 from disk 7.

Figs. 8 to 10 illustrate a modified form of hammer 10b, embodying the invention, which is not only reversible end for end about an axis radial to the rotor shaft 6 but also side for side about an axis parallel to the rotor shaft.

Hammer 10b, as illustrated, is a one piece unit of cast or welded construction and comprises a pair of parallel oppositely, facing, spaced, generally rectangular breaker bar portions 50 and 51 which may be considered as having opposed generally parallel spaced rear surfaces 50' and 51' and impact faces 50" and 51".

Provided respectively at the ends of hammer 10b are longitudinal channel portions 52 and 53 which are formed between the rear surfaces 50' and 51' of bar portions 50 and 51. Channel portion 53 has an opening through the end surface 54 of hammer 10b for receiving therethrough the head and neck portions of a hammer 9.

Provided intermediate the ends and extending transversely through hammer 10b is an assembly slot 55 which is formed between the rear surfaces 75 50' and 51' of the bar portions 50 and 51 for re-

5

ceiving the head and neck portions of a hammer arm 9 from either radial direction. Channel portion 52 has an opening, communicating longitudinally with assembly slot 5, through which the head and neck portions of a hammer arm 9 may be received.

In each of the channel portions 52 and 53 there is provided two pairs of horizontally opposite, vertically spaced ridges 56, 56' and 57, 57' which project from rear surfaces 58' and 51' of bar portions 50 and 51. The crests of each pair of horizontally opposite ridges are spaced apart a distance less than the width of the head portion of a hammer arm 9 but greater than the width of the neck portion. The two pairs of ridges in each channel portion are spaced vertically a distance slightly greater than the radial height of the head portion of a hammer arm 9.

The bars 50 and 51 are connected at the left hand end by wall like abutment means 58 positioned longitudinally adjacent channel portion 52. Spaced from the right hand end of hammer 10b by a distance which may be somewhat greater than the axial length of the head portion of a hammer arm 9, for use with which it is designed, is a similar wall or abutment means 59, positioned between assembly slot 55 and channel portion 53. Parallel strut members 60 and 60', arranged perpendicular to bar portions 50 and 51 and extending longitudinally between assembly slot 55 and abutment means 59, may be provided when additional strength is required and/or to serve as a mooring for a locking device as will appear hereinafter.

The spacing between rear surfaces 58' and 51' of bar portions 50 and 51 is slightly greater than the width of the head of a hammer arm 9 for use with which it is designed, and the lengths of the pairs of ridges 56 and 56' in channel portion 52 which extend from abutment means 58 are so chosen that there is sufficient open space between the ends of such ridges and abutment means 59, or the ends of strut members 60 and 60' if they are present, to form assembly slot 55 for receiving the head portion of a hammer arm 9 during assembly.

In effect, hammer 10b will be seen to comprise a block like article having an assembly slot 55, extending through it intermediate the ends of the hammer, which slot is wide and long enough to accommodate the head of a hammer arm 9. It will also be seen that the pairs of ridges 56, 56' and 57, 57' create the effect of two narrower slots, channel portions 52 and 53, with channel portion 52 adjoining assembly slot 55 and channel portion 53 being adjacent the right hand end of hammer 10b. Each of the channel portions 52 and 53 accommodate, respectively, the heads of hammer arms 9 with the neck portions extending in a radial direction between opposed crests of pairs of ridges 56 and 57 or in the opposite radial direction between opposed crests of pairs of ridges 56' and 57'.

Various locking arrangements to prevent longitudinal displacement of hammer 10b relative to hammer arms 9 may be devised and one such arrangement is shown in Fig. 8. In this illustration strut members 60 and 60' are utilized as a mooring for a locking assembly comprising a plate 61 having a generally L-shaped cross section and a plate 62 having a generally crank shaped cross section. With the hammer arms 9 in the position shown in Fig. 8, plate 61 is positioned so that one portion abuts the head portion of hammer arm 9 and the portion normal thereto abuts the lower side of strut member 60'. Plate 62 is then

6

positioned so that its parallel portions respectively abut plate 61 and the upper side of strut member 60. The plates have aligned holes for receiving a threaded bolt 63 which is engaged by a nut.

Disassembly of hammer 10b from arms 9 is readily accomplished by first removing the locking assembly, sliding hammer 10b to the left until the head of the left hand hammer arm 9 is in assembly slot 55 and then lifting the hammer radially away from arms 9. Hammer 10b may then be reversed end for end or side for side so as to present any one of the four edges as a leading edge, and again be mounted on hammer arms 9 without disconnecting the arms from disk 7.

Figs. 11 and 12 illustrate a hammer 10c which is substantially the same as hammer 10b except that it is adapted to cooperate with a modified form of locking means.

The locking means illustrated comprises a threaded bolt 70 which extends through a hole in bar portions 50c and 51c that is positioned to the right of the longitudinal space occupied by the head portion of the left hand hammer arm 9. Recesses may be provided in the outer surfaces of bars 50c and 51c to accommodate, respectively, the head of bolt 70 and a nut 71. Bolt 70 performs the same function in this instance as the locking means illustrated and described in connection with hammer 10b.

While specific apparatus is described and illustrated herein, it will be understood that the present invention includes such modifications and equivalents as may readily occur to persons skilled in the art to which it appertains, within the scope of the appended claims.

It is claimed and desired to secure by Letters Patent:

1. A hammer for a rotary impact breaker of the type which has a pair of parallel, radially extending hammer arms each having at the radially outer end thereof an enlarged head portion and an adjacent relatively narrow neck portion, said hammer comprising: a pair of elongated, spaced, generally rectangular breaker bar portions having oppositely facing impact surfaces and rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for receiving the head and neck portions of one of said arms from a radial direction; said rear surfaces forming therebetween, at the end of said hammer opposite said first channel portion, a second longitudinally extending channel portion which communicates with said assembly slot to allow the head and neck portions of one of said arms in said slot to enter said second channel portion; and at least two longitudinally extending ridges in each of said channel portions projecting respectively from said rear surfaces of said bar portions, the crests of said ridges being spaced transversely apart a distance less than the width of the head portion of one of said arms but greater than the width of said neck portion.

2. The combination of claim 1 including two wall like abutment means for respective engagement with the head portions of said arms, one of said abutment means being positioned at one end of said hammer adjacent said second channel portion and the second of said abutment means

being positioned between said assembly slot and said first channel portion.

3. A hammer for a rotary impact breaker of the type which has a pair of parallel, radially extending hammer arms each having at the radially outer end thereof an enlarged head portion and an adjacent relatively narrow neck portion, said hammer comprising: a pair of elongated, spaced, generally rectangular breaker bar portions having oppositely facing impact surfaces and rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for receiving the head and neck portions of one of said arms from a radial direction; said rear surfaces forming therebetween, at the end of said hammer opposite said first channel portion, a second longitudinally extending channel portion which communicates with said assembly slot to allow the head and neck portions of one of said arms in said slot to enter said second channel portion; at least two longitudinally extending ridges in each of said channels projecting respectively from said rear surfaces of said bar portions, the crests of said ridges being spaced apart a distance less than the width of the head portion of one of said arms but greater than the width of said neck portion; and said hammer having portions thereof formed to receive locking means for limiting relative longitudinal movement between said hammer and arms when assembled.

4. A hammer for a rotary impact breaker of the type which has a pair of parallel, radially extending hammer arms each having at the radially outer end thereof an enlarged head portion and an adjacent relatively narrow neck portion, comprising: an elongated bar of generally inverted U-shaped cross section having a pair of elongated, spaced, generally rectangular breaker bar portions and a bridge portion connecting and extending longitudinally between the upper parts of said bar portions, said bar portions having oppositely facing impact surfaces and rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for receiving the head and neck portions of one of said arms from a radial direction opposite said bridge portion; said rear surfaces forming therebetween, at the end of said hammer opposite said first channel portion, a second longitudinally extending channel portion which communicates with said assembly slot to allow the head and neck portions of one of said arms in said slot to enter said second channel portion; and at least two longitudinally extending ridges in each of said channel portions projecting respectively from said rear surfaces of said bar portions, the crests of said ridges being spaced apart a distance less than the width of the head portion of one of said arms but greater than the width of said neck portion.

5. The combination of claim 4 including two wall like abutment means for respective engagement with the head portions of said arms, one of

said abutment means being positioned at one end of said hammer adjacent said second channel portion and the second of said abutment means being positioned between said assembly slot and said first channel portion.

6. A hammer for a rotary impact breaker of the type which has a pair of parallel, radially extending hammer arms each having at the radially outer end thereof an enlarged head portion and an adjacent relatively narrow neck portion, comprising: an elongated bar of generally inverted U-shaped cross section having a pair of elongated, spaced, generally rectangular breaker bar portions and a bridge portion connecting and extending longitudinally between the upper parts of said bar portions, said bar portions having oppositely facing impact surfaces and rear surfaces; said rear surfaces forming therebetween, adjacent one end of said hammer, a first longitudinally extending channel portion having an end opening for receiving the head and neck portions of one of said arms through said one end of said hammer; said rear surfaces forming therebetween and intermediate the ends of said bar portions an assembly slot for receiving the head and neck portions of one of said arms from a radial direction opposite said bridge portion; said rear surfaces forming therebetween, at the end of said hammer opposite said first channel portion, a second longitudinally extending channel portion which communicates with said assembly slot to allow the head and neck portions of one of said arms in said slot to enter said second channel portion; and at least two longitudinally extending ridges in each of said channel portions projecting respectively from said rear surfaces of said bar portions, the crests of said ridges being spaced apart a distance less than the width of the head portion of one of said arms but greater than the width of said neck portion; and said hammer having portions thereof formed to receive locking means for limiting relative longitudinal movement between said hammer and arms when assembled.

7. A hammer for a rotary impact breaker of the type which has a pair of parallel, radially extending hammer arms each having at the radially outer end thereof an enlarged head portion and an adjacent relatively narrow neck portion, comprising: an elongated bar of generally inverted U-shaped cross section having a pair of elongated, spaced, generally rectangular breaker bar portions and a bridge portion connecting and extending longitudinally between the upper parts of said bar portions, said bar portions having oppositely facing impact surfaces and rear surfaces; a pair of longitudinally extending ribs projecting respectively from the lower edges of said rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for receiving the head and neck portions of one of said arms from a radial direction opposite said bridge portion; said rear surfaces forming therebetween, at the end of said hammer opposite said first channel portion, a second longitudinally extending channel portion which communicates with said assembly slot to allow the head and neck portions of one of said arms in said slot to enter said second channel portion; at least two

longitudinally extending ridges in each of said channel portions projecting respectively from said rear surfaces of said bar portions, the crests of said ridges being spaced apart a distance less than the width of the head portion of one of said arms but greater than the width of said neck portion; and a generally rectangular retainer slot formed between said rear surfaces normal to said bridge portion so as to intersect said ribs and ridges in said first channel at a point in 10 proximity to the end of said hammer, said retainer slot having an opening opposite said bridge portion for receiving a generally rectangular locking retainer plate.

8. A hammer for a rotary impact breaker of 15 the type which has a pair of parallel, radially extending hammer arms each having at the radially outer end thereof an enlarged head portion and an adjacent relatively narrow neck portion, comprising: a pair of elongated, spaced, 20 generally rectangular breaker bar portions having oppositely facing impact surfaces and rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for 25 receiving the head and neck portions of one of said arms from either radial direction; said rear surfaces forming therebetween, at the end of 30 said hammer opposite said first channel portion, a second longitudinally extending channel portion which communicates with said assembly slot to allow the head and neck portions of one of 35 said arms in said slot to enter said second channel portion; and at least two transversely opposite, radially spaced pairs of ridges in each of said channel portions projecting from said rear surfaces of said bar portions, the crests of each 40 pair of transversely opposite ridges being spaced apart a distance less than the width of the head portion of one of said arms but greater than the width of said neck portion and said pairs of said ridges being radially spaced apart a distance slightly greater than the radial height of said head portion; and said hammer having portions thereof formed to receive locking means for limiting relative longitudinal movement between said hammer and arms when assembled.

9. The combination of claim 8 including two 50 wall like abutment means for respective engagement with the head portions of said arms, one of said abutment means being positioned at one end of said hammer adjacent said second channel portion and the second of said abutment means being positioned between said assembly slot and said first channel portion.

10. The combination of claim 9 including a 55 pair of strut members arranged perpendicular to said bar portions and extending between said 60

assembly slot and said second of said abutment means for receiving locking means for limiting relative longitudinal movement between said hammer and arms when assembled.

11. The combination of claim 9 in which a transversely extending bolt hole is formed in and normal to said bar portions at a point between said assembly slot and said second channel portion for receiving bolt means for limiting relative longitudinal movement between said hammer and arms when assembled.

12. A hammer for a rotary impact breaker of the type which has a pair of parallel, radially extending hammer arms each having at the radially outer end thereof an enlarged head portion and an adjacent relatively narrow neck portion, comprising: a pair of elongated, spaced, generally rectangular breaker bar portions having oppositely facing impact surfaces and rear surfaces; said rear surfaces forming therebetween, adjacent one end of said hammer, a first longitudinally extending channel portion having an end opening for receiving the head and neck portions of one of said arms longitudinally through said one end of said hammer; said rear surfaces forming therebetween and intermediate the ends of said bar portions an assembly slot for receiving the head and neck portions of one of said arms from either radial direction; said rear surfaces forming therebetween, at the end of said hammer opposite said first channel portion, a second longitudinally extending channel portion which communicates with said assembly slot to allow the head and neck portions of one of said arms in said slot to enter said second channel portion; at least two transversely opposite, radially spaced pairs of ridges in each of said channel portions projecting respectively from said rear surfaces of said bar portions, the crests of each pair of transversely opposite ridges being spaced apart a distance less than the width of the head portion of one of said arms but greater than the width of said neck portion and said pairs of said ridges being radially spaced apart a distance slightly greater than the radial height of said head portion; and said hammer having portions thereof formed to receive locking means for limiting relative longitudinal movement between said hammer and arms when assembled.
